UNITED STATES PATENT OFFICE.

FORTUNATO LEVY, OF PARIS, FRANCE, ASSIGNOR TO GENERAL CARBONIC CO., OF BROOKLYN, NEW YORK, A CORPORATION OF NEW YORK.

APPARATUS FOR SPRAYING OR ATOMIZING LIQUIDS OR LIQUID COMPOSITIONS SUCH AS PAINTS.

1,210,500.

Specification of Letters Patent.

Patented Jan. 2, 1917.

Original application filed December 21, 1914, Serial No. 878,309. Divided and this application filed April 19, 1915. Serial No. 22,371.

To all whom it may concern:

Be it known that I, FORTUNATO LEVY, a subject of the Sultan of Turkey, and resident of Paris, France, have invented certain new and useful Improvements in Apparatus for Spraying or Atomizing Liquids or Liquid Compositions Such as Paints, of which the following is a specification.

This invention relates to apparatus for spraying or atomizing liquids or liquid compositions such as paints, and is a division of my United States application for patent Serial No. 878,309, filed December 21st, 1914.

The apparatus is particularly adapted for carrying out the method of painting described in my United States Patent No. 1,128,697.

The invention consists in the improvements in devices of this character herein-after described with reference to a preferred embodiment in the accompanying part diagrammatic, part sectional drawing, and more particularly pointed out in the appended claims.

Referring to the drawing, it will be seen that the installation comprises the following devices: the liquid carbon dioxide container 1 containing the liquid carbon dioxide or other gas under pressure, the gasifier 2 including the heating means 3, the expander 4, the receptacle 5 for the liquid composition and the atomizing tool 6 for applying said composition. It will be understood that the liquid gas in the receptacle 1 passes into the gasifier 2 where it is heated by the heating means 3; from the gasifier it passes to the expander 4 where the pressure of the gas is reduced, and the reduced-pressure gas is returned to the gasifier for reasons herein-after explained. After being reheated, the gas passes to the painting or atomizing tool where it atomizes the liquid paint composition, and a portion of the gas is supplied to the paint receptacle in well-known manner so as to force the paint under pressure into the painting tool.

With this understanding of the operation of the system, the various operating members thereof will now be described.

The liquid gas container 1, which is made strong enough to withstand the internal pressure to which it is subjected, but the dimensions of which are such that it can be

transported with ease, is provided with a special outlet or valve which prevents freezing of the liquid gas as it passes out of the container. In the normal positions of said container, that is, the positions in which the container is filled and transported before being used in my improved installation, this outlet may be regarded as being located at the top of the container; but when used in connection with my system, the container is preferably inverted so that the liquid passes out from its lower end.

The preferred form of outlet from the container illustrated herein comprises a central tubular member 7 and an outer casing or inverted cylindrical member 8 communicating at its lower end with the container 1 through passages 9 and at its upper end with the said tubular member by means of passages 10. The tubular member 7 is secured in position by screwing it on the plug 11 which keeps the whole assemblage in vertical position inside the container. The liquid carbon dioxide in the annular space between the casing 8 and the tubular member 7 passes through the passages 10, and flows down through the central passage 12 whence it passes out through the pipe 2. It then flows through the pipe 13 to the gasifier 2 which will now be more specifically described.

The gasifier consists of a horizontal metal member 14 of rectangular shape in section, in which there is formed longitudinally a helical passage 15, produced by tapping one or more square threads and bounded internally by a cylindrical hollow member 16 closed at both ends. The liquid carbon dioxide arrives at one end of the passage 15 through said pipe 13 and it passes out at the other end in the gaseous state through an outlet 17. The burner 18, utilizing any suitable fuel, and preferably a suitable mineral oil, is located in a chamber having the shape of an inverted truncated pyramid, the base of which is formed by the member 14. By this means a good distribution of the heat produced by the burner is obtained.

The hot gas passes through vertical passages 20 formed in the thickness of the member 14 on each side of the helical passage, and opening directly into a chamber 105 containing coiled pipes 21, 22, 23 which

may be three in number, as in the example shown, for heating the gasified liquid. These coiled pipes are connected to the outlet 17 of the gasifier by means of a pipe 24.

5 The chamber 20 is of trapezoidal form in section as shown in Fig. 1, and the coiled pipes 21, 22, 23 are arranged parallel to the inclined outer walls 25 of said chamber, which are formed with holes 26 for the escape of the hot air. The carbon dioxide 10 coming through the pipe 24 rises in the coiled pipe 21 and passes down again through the coiled pipe 22. At the end of the coiled pipe 22 the gas passes out of the heating chamber through a pipe 27 and 15 enters the expander 4, which is an expanding device of any suitable construction, and which reduces the gas to the desired pressure for use. After the gas has left the reducing device or expander, it is again 20 heated to compensate for the cooling produced by the additional expansion which takes place in the expander. The gas on leaving the expander 4 through a pipe 28 passes into the lower part of the coiled pipe 23; it passes finally from the heating chamber through a pipe 29 on its way to the tool 25.

6. The pipe 29 is provided with a branch pipe 30 and containing the reducing valve 31 leads to the top of the paint receptacle 5, and by suitably manipulating the valve 31 the paint can be forcibly fed at the desired pressure to the painting device through the flexible pipe 32, where it is 30 atomized by the carbon dioxide gas from the flexible connection 33 connected to said pipe 29.

What I claim is:—

1. In an apparatus of the kind described, 40 the combination of a receptacle for carbon dioxide, an atomizing tool, a receptacle for the substance to be atomized, means for feeding said substance to said tool, means for heating the carbon dioxide, means for 45 reducing the pressure of the heated carbon dioxide, and means for supplying said carbon dioxide to said tool.

2. An apparatus of the kind described, 50 comprising a receptacle for carbon dioxide, means for heating said carbon dioxide, means for reducing the pressure of the carbon dioxide thus heated, an atomizing means, means for leading the substance to be atomized to said atomizing means, and means for 55 leading said carbon dioxide gas to said atomizing means.

3. An apparatus of the kind described, 60 comprising a receptacle for carbon dioxide, heating means, means for reducing the pressure of the heated carbon dioxide, means for leading carbon dioxide from said receptacle to said heating and pressure-reducing means, an atomizing means, a receptacle for the substance to be atomized, means for 65 feeding said substance from said receptacle

to said atomizing means, and means for leading said carbon dioxide from said heating and pressure-reducing means to said atomizing means.

4. Apparatus of the kind described, comprising a receptacle for carbon dioxide, an outlet located below said receptacle, means for heating said carbon dioxide, means for reducing the pressure of the heated carbon dioxide, means for leading the carbon dioxide from said container to said heating means and pressure-reducing means, an atomizing means, means for leading the substance to be atomized to said atomizing means, and means for leading the carbon dioxide from said heating and pressure reducing means to said atomizing means. 70

5. An apparatus of the kind described, comprising a receptacle containing a liquefied gas, means for heating said liquefied gas, means for reducing the pressure of said gas after heating, an atomizing means, means for leading the substance to be atomized to said atomizing means, and means for leading said gas from said heating and pressure-reducing means to said atomizing means. 80

6. Apparatus of the kind described, comprising a receptacle for carbon dioxide, means for heating and reducing the pressure of said carbon dioxide, means for re-heating said carbon dioxide, an atomizing means, means for leading said carbon dioxide under pressure from said heating, pressure-reducing and re-heating means to said 90 atomizing means.

7. An apparatus of the kind described, comprising in combination a receptacle for carbon dioxide, a heating device, a pressure-reducing device, an atomizing tool, a receptacle for the substance to be atomized, means for leading carbon dioxide from said carbon dioxide receptacle to said heating and pressure-reducing devices, means for leading the carbon dioxide from said heating and pressure-reducing devices to said atomizing tool, and means for feeding the substance to be atomized from said receptacle to said atomizing tool. 105

8. An apparatus of the kind described, comprising a receptacle for carbon dioxide, a heating device, a pressure-reducing device, a re-heating device, an atomizing tool, a liquid composition receptacle, means for leading carbon dioxide from said carbon dioxide receptacle to said heating and pressure-reducing devices, means connecting the pressure-reducing device with the re-heating device, flexible means for leading the carbon dioxide gas from the heating, pressure-reducing and re-heating devices to the atomizing tool, and flexible means for leading the composition from the liquid composition receptacle to the atomizing tool. 110

9. An apparatus for atomizing a liquid 120

- composition such as paint, comprising a portable receptacle for carbon dioxide, a burner, a heating chamber above said burner, a pressure-reducing device communicating with said heating chamber, an atomizing tool, a liquid composition receptacle, means for leading carbon dioxide from said portable receptacle to said heating chamber and pressure-reducing device, means for leading the carbon dioxide from said heating chamber and pressure-reducing device to said atomizing means, and means for leading the liquid composition from said liquid composition receptacle to said atomizing tool.
10. An apparatus for atomizing a liquid composition such as paint, comprising a portable receptacle for carbon dioxide, heating and pressure reducing means connected to said portable receptacle, an atomizing means, and means for leading carbon dioxide under pressure from said heating and pressure reducing means to said atomizing means, a liquid composition receptacle, and means for leading liquid composition from said receptacle to said atomizing means.
15. A spraying apparatus of the kind described comprising a portable receptacle for carbon dioxide, heating pressure reducing and re-heating means connected to said portable receptacle, a spraying tool, means for leading carbon dioxide from said heating, pressure reducing and re-heating means to said atomizing means, and means for leading the material to be sprayed from said receptacle to said spraying means.

20. In an apparatus of the kind described, the combination of a receptacle for carbon dioxide, an atomizing tool, a receptacle for the substance to be atomized, means for feeding said substance to said tool, a heat-

ing coil, means for heating said coil, means for reducing the pressure of carbon dioxide heated in said coil, and means for supplying said carbon dioxide to said tool.

13. In an apparatus of the kind described, the combination of a receptacle for carbon dioxide, an atomizing tool, a receptacle for the substance to be atomized, means for feeding said substance to said tool, means for heating the carbon dioxide, a pressure-reducing valve, means for connecting the heating means with the pressure-reducing valve, and means connecting the pressure-reducing valve with the tool.

14. Apparatus of the kind described, comprising a receptacle for carbon dioxide, a heating coil for said carbon dioxide, a pressure-reducing valve connected to said heating coil, a reheating coil connected to said pressure-reducing valve, an atomizing means, means for leading said carbon dioxide under pressure from said re-heating coil to said atomizing means, and means for leading the substance to be atomized to said atomizing means.

15. Apparatus of the kind described, comprising a receptacle for carbon dioxide, means for heating said carbon dioxide, a pressure-reducing valve, means for reheating said carbon dioxide, an atomizing means, means for leading said carbon dioxide from said re-heating means to said atomizing means, and means for leading the substance to be atomized to said atomizing means.

Signed at New York city, in the county of New York and State of New York, this seventeenth day of April, A. D. 1915.

FORTUNATO LEVY.
